GLUE DISPENSING ARTICLE

Sue B. Carstensen, Redondo Beach, Calif.

Application March 10, 1952, Serial No. 275,833

1 Claim. (Cl. 206—56)

1 The present invention relates generally to glue dispensing articles, and more particularly to a novel glue dispensing article wherein the glue or adhesive is disposed for especially convenient use. Glutinous adhesives of various types find wide usage today in offices, schools, and homes. Most of these adhesives are merchandised in either bottles or pliable metallic tubes. The use of such containers involves certain disadvantages. For example, the bottles are liable to be overturned, whereupon their contents may spill onto the furniture, floor or rug; this is especially liable to occur where children are concerned. Additionally the bottles are susceptible to easy breakage, with the consequent mess and the loss of adhesive which normally follows.

The metallic tubes, on the other hand, while not susceptible to spillage or breakage, are subject to other disadvantages. For example, the caps of these tubes are of small dimensions and easily lost. When this occurs the glue within the tube will either flow out of the neck of the tube or else it will become dried to the point where it will no longer flow. Moreover, if the tube is inadvertently stepped upon, its contents will become displaced therefrom and run onto the floor or rug. Since these tubes are of metallic construction their manufacture may be hindered by virtue of the periodic metal shortages which may occur from time to time.

Another disadvantage inherent in the bottle and tube containers is their unattractive appearance after a comparatively short period of use. This is especially true of the bottles where the excess glue has run down over their sides.

It is a major object of the present invention to provide a novel glue dispensing article from which inadvertent loss of glue cannot occur.

Another object of the present invention is to provide a glue dispensing article primarily adapted for the occasional use of glue wherein the glue may be maintained for an indefinite time in prime condition.

It is another object of this invention to provide a glue dispensing article which is especially easy to use, does not require vital materials in its fabrication, and is inexpensive to manufacture.

A further object of the present invention is to provide a glue dispensing article which is of attractive appearance in its original condition, and which is not rendered unattractive by usage, and from which the exact quantity of glue desired may be obtained.

These and other objects and advantages of the present invention will become apparent from the

2 following description of a preferred embodiment thereof, taken in conjunction with the appended drawings, wherein:

Figure 1 is a perspective view of a glue dispensing article embodying the present invention and showing said article ready for use in a gluing operation;

Figure 2 is a fragmentary, perspective view of the glue dispensing article of Figure 1, but showing said article while being prepared for use; and,

Figure 3 is an enlarged fragmentary top view of the glue dispensing article shown in Figures 1 and 2 and taken partly in section along line 3—3 of Figure 2.

Referring now to the drawings, the glue dispensing article embodying the present invention is seen to comprise generally an inner core 10 of glutinous adhesive, an intermediate covering of flexible metallic foil 12, and an external strip 14 of sheet material disposed over the intermediate covering 12.

More particularly, the inner core 10 will preferably comprise a cylinder of a suitable glutinous adhesive of a generally form-sustaining type, which adhesive is adapted to harden upon exposure to the atmosphere for a predetermined time. Several glutinous adhesives of this nature are commercially available and will be familiar to those skilled in the art. The particular compositions of such glutinous adhesives are not intended to fall within the scope of the present invention.

The intermediate covering of the metallic foil 12 is shown disposed concentrically about the core 10. This foil is adapted to be progressively removed from the core 10 so as to provide piece-meal exposure thereof. In order to facilitate such progressive removal, the foil 12 will preferably include a longitudinal separation 16. The foil will also preferably be formed with a plurality of longitudinally spaced circumferential perforations 18. These perforations serve to further facilitate the progressive removal of the foil 12 from the core 10. Various types of flexible metallic foil may be utilized to form the intermediate covering, however, it has been determined that a light gauge aluminum foil is especially well suited for this purpose.

The external strip 14 is preferably formed of an elongated piece of paper or paper-like material wound helically upon the foil with its turns in overlapping relationship and adhesively connected so as to form a tube. This external strip 14 serves as supporting medium for the core 10 and its foil covering 12. The juxtaposed margins

of adjacent turns of the strip material are readily separable from each other by the unwinding thereof. In this manner the strip material is seen to be readily progressively removable from the intermediate covering 12 whereby to provide 5 the piecemeal exposure thereof.

In order to facilitate the unwinding of the strip material 14, it has been found desirable to dispose a longitudinally extending flexible element, such as a string 20, between the outer surface of the foil 12 and the inner surface of the strip material 14. With this arrangement it is only necessary to pull the string 20 radially outwardly away from the body of the glue dispensing article in order to progressively cut through the strip material, as indicated in Figure 2. This action will free the desired number of turns of the strip material whereby the unwinding thereof may take place.

In using the glue dispensing article of the present invention, a sufficient number of turns of the strip material 14 is unwrapped whereby will be exposed a portion of the foil 12. Next, the end flap 22 of the foil is folded outwardly away from its original position shown in Figures 2 and 3, whereby to expose the end of the adhesive 10, as shown in Figure 1. The glue dispensing article may then be grasped by its main body 24 to dispense a layer of the adhesive 10 upon a desired object or surface.

At such time as it becomes necessary to expose an additional length of adhesive, the string 20 may be pulled through one or more additional turns of the strip material 14 whereby to permit the unwinding thereof from about the foil 12. The portion of this foil exposed thereby is then removed from the outside of an additional length of the adhesive. This removal process will be facilitated by means of the longitudinal separation 16. Moreover, whenever the exposed length of foil reaches a length which hinders the efficient manipulation of the glue dispensing article, a desired portion of this exposed length can be readily removed by readily tearing the foil along one of the circumferential perforations 18.

At the completion of the gluing operation, it is anticipated that the end portion of the exposed foil be folded over the exposed portion of the adhesive core 10. In this manner the adhesive will be sealed against contact with the atmosphere, which contact would result in the hardening thereof. When the glue dispensing article is to be again utilized, the foil may then be unfolded so as to expose the adhesive.

It will be apparent to those skilled in the art that various modifications and changes may be made with respect to the disclosed preferred em-

bodiment. For example, although metallic foil is described as being utilized for the intermediate covering 12, it should be possible to utilize for this purpose almost any material which when folded over the exposed portion of the adhesive core 10 will substantially retain its folded configuration so as to thereby seal the core against contact with the atmosphere. Such modifications and changes, however, are not believed to depart from the spirit of the invention or the scope of the appended claim.

I claim:

A glue dispensing article, comprising: an inner core of form-sustaining glutinous adhesive; an intermediate covering of flexible metallic foil, said foil being progressively removable from said core so as to provide piecemeal exposure thereof; an external strip of sheet material wound helically upon said foil with its turns in overlapping relationship and adhesively connected to form a tube therearound; and a longitudinally extending string disposed between the outer surface of said foil and the inner surface of said strip material, said string being movable radially outwardly of the article so as to progressively cut through said material to thereby permit its being unwound progressively about said foil, and the portion of said foil from which said strip material has been removed being foldable over the exposed portion of said core whereby to seal it against contact with the atmosphere until such time as said core is to be again utilized, said foil including a longitudinal separation adapted to facilitate its removal from said core, said foil also including a plurality of longitudinally spaced circumferential perforations to facilitate progressive removal of said foil as said core is exposed.

SUE B. CARSTENSEN.
